PROCESS FOR THE PHOTOMECHANICAL
REPRODUCTION OF ANIMAL SKINS AND
THE LIKEKarl Eichstädt, Berlin-Friedenau, Germany, as-
signor to Oxford Varnish Corporation, De-
troit, Mich., a corporation of MichiganNo Drawing. Application September 3, 1935,
Serial No. 39,069. In Germany September 11,
1934

3 Claims. (Cl. 41—26)

The present invention relates to a process for 5
decorating surfaces in simulation of animal skins,
shagreens and the like. More especially, the
invention relates to a process for treating animal
skins and the like to enable them to be photo-
mechanically reproduced in such a manner that
the reproduction will simulate the natural arti-
cles, even to the finer tones and natural glow
or sheen-like appearances of the original skin
10 or furs.

Heretofore, animal skins, fine leathers, as,
for example, squirrel, snake and the like, have
been photomechanically reproduced to simulate
leather. Such reproduction has been accom-
15 plished by means of well-known leather printing
processes, such as direct or offset printing pro-
cesses. In making such imitations it has been
found that although the actual coloring of the
individual skins may be simulated in a general
20 way, the finer tones of the fur and the leather
grains which give a natural appearance to the
original article, are not readily imitated. It is
therefore an object of the present invention to
so reproduce the natural skins and leather that
25 these defects may be overcome and the reproduc-
tion given a natural appearance.

Ordinarily, the natural skin or leather is photo-
graphed and an offset printing plate made from
such photograph by the well-known photome-
30 chanical process. This plate thereafter is gen-
erally used in an offset printing process, with inks
of suitable colors, to reproduce or imitate the nat-
ural article photographed. I have found that
even though greatest of care is used in photo-
35 graphing and making the printing plate, never-
theless the natural appearance of the simulated
results is lacking. Briefly, I find that by treat-
ing the skins or furs to be simulated before
photographing them, I am able to obtain a print-
40 ing plate which may be used in the ordinary
printing processes and which will simulate or re-
produce the design of the skin or fur with great
accuracy and at the same time simulate the nat-
ural appearances not found when ordinary
45 photomechanical methods are used to produce
the printing plate without first treating the skin
or fur. This, therefore, is a more specific object
of the present invention.

Other objects of the invention will become
50 more apparent from the following description,
and the essential novel characteristics of the
method will be set forth in the claims.

According to the present invention, I treat
the skins or furs to be simulated with a waxed
55 polishing stone, before making a photographic

reproduction from which the printing plate is
made by the usual photomechanical method. To
this polishing stone I apply a colorless wax-like,
non-lubricating ingredient in small amounts,
and transfer this ingredient to the skin or fur 5
to be simulated by the stone. Such waxes and
ingredients may be a common polishing wax,
either of organic or synthetic origin, and when
transferred to the skin or fur by means of the
stone, will adhere only to the upper layer or 10
elevated scales and give them a greater brilliancy
so that a decidedly greater contrast is obtained.
Depending upon the color of the skin or fur, I
may also color the wax, so that the color con-
trast on the article being simulated, may be en- 15
hanced. In certain instances, as, for instance,
white furs or skins, I find that the tonal depths
are lacking when ordinary methods of reproduc-
tion are used. I also find that by using a dark
colored wax on the light colored grain, before 20
photographing the fur or skin and making the
printing plate from a negative photogravure re-
sist rather than from a positive photogravure re-
sist, as is ordinarily done, I am able to accentu- 25
ate both the depth of the tones. This accentua-
tion, however, acts to more nearly simulate the
natural article, and does not exaggerate the
tones.

In skins and furs and less pronounced color
30 designs, the use of this process results in an im-
provement, in that the contrast in the skin or
fur may be heightened by using colors with
stronger contrasting tones upon the less active
shades of furs or skins. In skins having a pro- 35
nounced design, but whose colors are not suffi-
ciently active for insuring color contrast on pho-
tographic films, such as for instance, red, I find
that by polishing with colors which will cause
40 greater activity on the film, I am able to produce
a printing plate which will produce prints more
closely simulating the original design in color
and tone.

I claim:

1. The process for decorating surfaces in simu-
lation of fine animal skins, leathers and the like,
comprising the step of treating such skins to
increase their polish and thereafter photo-
graphically reproducing a printing plate from
such article and transferring the design from the
printing plate to the surface to be decorated. 45
2. The process for decorating surfaces in simu-
lation of fine animal skins, leathers and the
like, comprising the step of treating such skins,
leathers and the like with a colorless wax-like
polish and thereafter photographically reproduc- 55

ing a printing plate from such article and transferring the design from the printing plate to the surface to be decorated.

- 5 3. The process for decorating surfaces in simulation of light colored animal skins, leathers and the like, comprising the step of applying a dark colored polishing wax to such skins, leathers and

the like and thereafter photographically reproducing a negative or reverse printing plate from such article and transferring the design from the reverse printing plate to the surface to be decorated.

KARL EICHSTÄDT.
